UNITED STATES PATENT OFFICE.

CHARLES LE GEYT FORTESCUE, OF PITTSBURGH, PENNSYLVANIA, ASSIGNOR TO WESTINGHOUSE ELECTRIC AND MANUFACTURING COMPANY, A CORPORATION OF PENNSYLVANIA.

ALTERNATING-CURRENT TRANSFORMER.

1,129,470.

Specification of Letters Patent.

Patented Feb. 23, 1915.

Original application filed August 2, 1909, Serial No. 510,854. Divided and this application filed October 8, 1910, Serial No. 586,100. Renewed May 27, 1914. Serial No. 841,349.

To all whom it may concern:

Be it known that I, CHARLES LE G. FORTESCUE, a subject of the King of Great Britain, and a resident of Pittsburgh, in the county of Allegheny and State of Pennsylvania, have invented a new and useful Improvement in Alternating-Current Transformers, of which the following is a specification, this application being a division of application Serial No. 510,854, filed August 2, 1909.

My invention relates to the windings and insulation of transformers which are adapted for use with very high-voltage circuits and it has for its object to provide a winding which is so connected, and insulation which is so constructed and associated with the winding, that the manufacturing cost of the transformer and the space occupied by it may be materially reduced, while, at the same time, its terminal voltage may be very high.

The single figure of the accompanying drawing is a sectional elevation of a transformer core and a winding arranged in accordance with my invention.

Referring to the drawing, the structure here shown comprises a substantially rectangular core 1, a low-potential winding 2 that is divided into two groups of coils which surround two opposite legs 3 and 4 of the core 1 and are separated therefrom by insulating sleeves 5, a primary winding composed of two groups 6 and 7 of relatively flat coils and insulating sleeves 8 and 9 located on the respective core legs, between the low and high-potential windings. The core legs 3 and 4 may be of any suitable form but are preferably cruciform in cross-section, in order to economize space and to reduce the mean length of turn in the coils.

In my copending application, Serial No. 510,854, filed August 2, 1909, of which this application is a division, and a co-pending application, Serial No. 586,096, filed of even date herewith, I have shown and described a transformer winding composed of two groups of coils which are so connected that the coils of both groups which are most remote from the core member are connected in series to the high-potential terminal of the transformer, certain of the connections be-

tween coils being effected by means of conducting plates which form parts of the insulation.

55

According to my present invention, I substitute for the conducting plates, a series of transformer turns 10 which are disposed in the insulating sleeves 8 and 9 to form a part of the main winding of the transformer and are connected in series with the transformer coils, whereby I secure the desired and proper distribution of stress in the insulation without the use of separate conducting plates or other auxiliary means. The coils, 65 which form parts of the insulating sleeves, are composed of a plurality of layers 11 each containing a substantially equal number of the turns 10. The turns in the high-voltage layers which are farthest from the core legs 70 are disposed side by side, and the turns of the other layers, from the outer ones inwardly, are spaced farther and farther apart, being quite widely separated in the inner layers nearest to the core legs. By this 75 means, the potential is properly distributed through the insulating bushings and the layers near the core legs are as efficiently utilized as those near the high-voltage coils. The intensity of the strain on each layer of 80 insulation and the distribution of stress therein is predetermined, since the potential of each point of the winding is fixed.

I claim as my invention:

1. In electrical apparatus, the combination with a low-potential body, and a relatively high-potential conductor, of an insulating structure disposed between said body and said conductor and comprising a plurality of concentric insulating cylinders and means constituting a part of the conductor for determining distribution of stress in the insulation.

85

2. In a transformer, the combination with a magnetizable core, and a winding therefor 95 having a plurality of coils arranged end to end, of an insulating sleeve disposed between said core and said winding and comprising a plurality of layers and a series of convolutions of electric conductor distributed between the layers, the convolutions of each layer being included electrically between pairs of the coils.

100

3. In electrical apparatus, the combina-

- tion with a low-potential body and a relatively high-potential conductor, of an insulating structure disposed between said body and said conductor and embodying 5 means constituting a part of the conductor for determining the distribution of stress in the insulation.
4. In an electrical device, the combination with a core, and an insulating sleeve, 10 surrounding the core, of a winding comprising a plurality of coils embedded in, and separated by, the insulating sleeve, the end convolutions of the coils being adjacent to the ends of the sleeve.
- 15 5. In an electrical device, the combination with a core, and an insulating sleeve surrounding the core, of a winding comprising a plurality of substantially concentric coils embedded in, and separated by, the insulating sleeve, the end convolutions of the coils being adjacent to the ends of the sleeve and the convolutions of the inner coils being spaced farther apart than those of the outer coils.
- 20 25 6. In an electrical device, the combination with a core, and an insulating sleeve that surrounds the core and is tapered from an intermediate point toward its ends, of a

winding comprising a plurality of coils embedded in, and separated by, the insulating 30 sleeve, the end convolutions of the coils being adjacent to the tapered ends of the sleeve.

7. In an electrical device, the combination with a core, and an insulating sleeve 35 surrounding the core and having stepped ends, of a winding comprising a plurality of coils embedded in, and separated by, the insulating sleeve, the end convolutions of the coils being adjacent to the ends of the 40 steps in the sleeve.

8. In an electrical device, the combination with a core, and an insulating structure surrounding the core having stepped ends, of a winding comprising a plurality of coils 45 separated by the insulating structure, the end convolutions of the coils being adjacent to the ends of the steps in the insulating structure.

In testimony whereof, I have hereunto 50 subscribed my name this 23rd day of Sept., 1910.

CHARLES LE GEYT FORTESCUE.
